UNITED STATES PATENT OFFICE.

HENRY H. BOGGS, OF SYRACUSE, NEW YORK.

CRUSHING-MACHINE.

SPECIFICATION forming part of Letters Patent No. 672,223, dated April 16, 1901.

Application filed July 5, 1900. Serial No. 22,468. (No model.)

To all whom it may concern:

Be it known that I, HENRY H. BOGGS, a citizen of the United States, and a resident of Syracuse, in the county of Onondaga, in the 5 State of New York, have invented new and useful Improvements in Crushing-Machines, of which the following, taken in connection with the accompanying drawings, is a full, clear, and exact description.

This invention relates to a machine which is intended more particularly for the purpose of crushing ice, although it may be employed for operating on other substances.

The object of the invention is to produce 15 a machine which shall be simple, strong, and durable in construction and at the same time very efficient in its operation.

To that end the invention consists in the novel construction and combination of the 20 component parts, as hereinafter fully described, and set forth in the claims.

In the annexed drawings, Figure 1 is a side elevation of my improved crushing-machine. Fig. 2 is a plan view, the arm which extends 25 from one of the jaws being broken away. Fig. 3 is an enlarged vertical transverse section on line X X in Fig. 2. Fig. 4 is an enlarged longitudinal section on line Y Y in Fig. 2. Fig. 5 is a vertical transverse section 30 on line Z Z in Fig. 1.

Referring to the drawings, A represents the supporting-frame, which may be of any desired form and is provided with the usual legs a a.

35 B denotes the main shaft, which is journaled in suitable boxes a' a', secured to the under side of the frame. At the intermediate portion of the shaft B is formed a crank C, and to the end of said shaft is secured the 40 driving-pulley C'.

D D' represent a pair of movable opposing jaws, between which the ice or other substance is placed to be crushed, which jaws receive their movement from the main shaft 45 B by mechanism which will be shortly explained.

On top of the frame A are mounted two pairs of plates b b and b' b', each pair being disposed at opposite sides of the frame. Said 50 plates are formed on their tops with journal-

boxes c c and c' c', respectively, and are attached to the frame by means of bolts d d.

A' A' represent two parallel vertical plates, which are disposed oppositely and are each formed at the lower edge with an ear d', having a stud e projecting therefrom, by which said plates are pivoted in the aforesaid journal-boxes c c. To the outer ends of the plates A' A' is secured the jaw D, preferably by means of bolts or screws f f. The opposing 60 jaw D' is disposed to move freely between said plates A' A' and is formed with ears f' f' at its lower end, each having a stud g projecting from it, by which the latter jaw is pivoted in the journal-boxes c' c'.

In order to adjust the jaws D D' toward and from each other when desired for the purpose of crushing the ice or other substance to fine or coarse particles, I form the aforesaid plates b b b' b' on their tops with projections h h h' h', 70 respectively, formed with eyes which are screw-threaded in opposite directions, and through said projections pass right-and-left screw-rods i i, formed with nuts i' i' between the projections by which to turn said rods, 75 whereby the plates can be shifted longitudinally on the frame A, and thus said jaws are moved. To permit said plates b b b' b' to be shifted, I provide the same with longitudinal slots a² a², through which the aforesaid bolts 80 d d pass, which bolts serve to clamp the plates in their required positions.

The jaws D D' consist, preferably, of plates formed on their opposing faces with pointed projections a³ a³; but they may be of any other 85 suitable form or construction.

B' B' denote a pair of parallel rock-arms, which are pivoted to a post b², as indicated at c², which post is mounted on top of the frame or, more directly, to a cross-bar d², 90 secured to the frame. Said rock-arms are formed at their respective ends with longitudinal slots e² e² and f² f².

From the aforesaid vertical plates A' A' extend a pair of horizontal parallel arms g³ g³, 95 preferably formed integral therewith, and to the free ends of said arms is rigidly secured a shaft h³ by means of nuts i³ i³, applied to the screw-threaded ends of the shaft. Said shaft h³ passes freely through the slots e² e² 100

of the rock-arms B' B' and is connected to the aforesaid crank C on the main shaft by means of a pitman B², which is pivoted to said crank and to the shaft h⁸ between the rock-arms, as 5 clearly shown in Fig. 2.

To the back of the jaw D' is rigidly secured one end of an arm D² by means of screws or bolts a⁴ a⁴, the opposite end of which arm is formed with an ear b⁴ on its under side, by 15 which it is pivotally and adjustably secured in the aforesaid slots f³ f³ in the outer ends of the rock-arms B' B', as indicated at c⁴.

I do not wish to be limited to the specific construction herein shown and described, as 15 the same may be modified to a great extent without departing from the spirit of my invention.

What I claim is—

1. In a crushing-machine, the combination 20 with a supporting-frame and main shaft, of a pair of oppositely-disposed vertical parallel plates pivoted to said frame, a jaw secured to the pivoted ends of said plates, a pair of arms extending from the other ends of the 25 plates, an opposing jaw pivoted to the frame and movable between said plates, a shaft rigidly secured to the free ends of said arms, a pitman connecting the latter shaft to the main shaft, an arm extending from the other 30 jaw, and a rock-arm connecting the latter arm to the aforesaid rigid shaft substantially as described.

2. In a crushing-machine, the combination 35 with a supporting-frame and the main shaft provided with a crank, of a pair of oppositely-disposed vertical parallel plates pivoted to said frame, a jaw secured to the pivoted ends of said plates, an opposing jaw pivoted to the

frame and movable between said plates, a pitman pivoted to the aforesaid crank and 40 connected to said plates, a rock-arm connected to said pitman, and an arm connecting said rock-arm and latter jaw substantially as described.

3. In a crushing-machine, the combination 45 of a pair of pivoted jaws, a main shaft provided with a crank, a pair of parallel arms connected to one of said jaws, a shaft rigidly secured to the free ends of said arms, a pitman pivoted at one end to said crank and at 50 its opposite end to the rigid shaft, a rock-arm formed with a longitudinal slot at each end, the slot at one end loosely engaging the rigid shaft, and an arm secured in the slot at the other end and attached to the other jaw substantially as described.

4. In a crushing-machine, the combination with the supporting-frame and the main shaft provided with a crank, a post secured to the frame, a pair of rock-arms pivoted to opposite sides of said post and having their end portions slotted longitudinally, a pair of pivoted jaws, a pair of arms extending from one of said jaws, a shaft rigidly secured to the free ends of said arms and passing loosely 65 through one end of the rock-arms, an arm extending from the other jaw and pivoted between the other ends of said rock-arms, and a pitman pivoted at one end to the aforesaid crank and at its opposite end to the rigid 70 shaft between the rock-arms substantially as described.

HENRY H. BOGGS.
